DESIGN FOR A MARIMBA

Clair O. Musser, Chicago, Ill., assignor to J. C.
Deagan Inc., Chicago, Ill., a corporation of Illinois

Application August 26, 1933. Serial No. 49,114

Term of patent 3½ years

To all whom it may concern:

Be it known that I, CLAIR O. MUSSER, a citizen of the United States of America, and a resident of Chicago, county of Cook, and State of Illinois, have invented a new, original, and ornamental Design for a Marimba, of which the following is a specification, reference being had to the accompanying drawing, forming a part thereof.

The single figure of the drawing is a perspective view of a marimba embodying my design.

I claim:

The ornamental design for a marimba, substantially as shown.

CLAIR O. MUSSER.
